CLAIM

The ornamental design for a compass, as shown and described.

DESCRIPTION

FIG. 1 is a perspective view of a compass showing my new design, the pencil depicted by means of broken lines being shown for illustrative purposes only and forming no part of the claimed design;

FIG. 2 is a front elevational view thereof;

FIG. 3 is a left side elevational view thereof;

FIG. 4 is a rear elevational view thereof;

FIG. 5 is a right side elevational view thereof; and,

FIG. 6 is a top plan view thereof.
